AUTOMATIC CONTROLLING MEANS FOR
FRACTIONATING TOWERS

Record R. Whitley, Texas City, Tex.

Application May 9, 1946, Serial No. 668,388

1 Claim. (Cl. 202—160)

1

This invention relates to automatic controlling means for a fractionating tower.

An object of the invention is to provide means of the character described whereby the heavier liquids may be relieved from the tower.

It is another object of the invention to provide means for automatically controlling the relief of said residual liquid resulting from the fractionating process, thereby controlling the specific gravity of the product.

A further object of the invention is to provide an automatic controlling equipment of the character described which will automatically regulate the relief of liquid from the tower irrespective of temperature variation.

With the above and other objects in view the invention has particular relation to certain novel features of construction, operation and arrangement of parts, an example of which is given in this specification and illustrated in the accompanying drawings, wherein—

Figure 1 is an enlarged, vertical, sectional view of an automatically operable, adjustable, flow controlling valve assembly employed; and,

Figure 2 is a fragmentary, vertical, sectional view of a fractionating tower equipped with the automatic controlling means.

Referring now more particularly to the drawings wherein like numerals of reference designate the same parts in each of the figures, the numeral 1 designates a fractionating tower having the conventional transverse trays, or partitions, 2 therein. These partitions have the tubular upstanding nipples 3 which are partially enclosed above by the conventional bubble caps 4 and leading downwardly from the trays are the overflow conduits 5.

Between the upper and lower trays 2 there is a transverse partition 6 extending entirely across the tower 1 and forming a side stream draw, or stripping, tray. This partition has a central opening and surrounding this opening and upstanding therefrom there are the vapor tubes 7. On opposite sides of the tower 1 there are the float chambers 8 and 9 which are of substantially similar construction. Extending laterally from the respective float chambers are the tubular arms 10 and 11 whose outer ends are closed. These arms are at an elevation to be partly filled with liquid from the corresponding float chamber.

Within said chambers are the respective floats 12 and 13 which are fixed to the inner ends of the respective float stems 14 and 15 which extend into the corresponding arms 10 and 11. The outer

2

end of the stem 14 has the yoke 16 fixed thereon whose arms embrace an adjusting rod 17, and are pivoted thereto.

Mounted on the arm 10 there is a tubular fitting 18 into which the upper end of the rod 17 extends and mounted in this fitting there is a hand wheel shaft 19 whose upper end has a hand wheel 20 fixed thereon.

The lower end of the shaft 19 is threaded into an internally threaded socket extending axially into the rod 17, as is illustrated in my copending application for Adjustable level control filed December 22, 1945 under Serial No. 637,043, so that by turning the shaft 19 the rod 17 and the corresponding end of the stem 14 may be adjusted up and down.

There is a relief pipe 21 whose arms are anchored to and extend through the wall of the tower 1. The free end of one of these arms is upwardly turned through the partition 6 and the free end of the other arm is downwardly turned into the tray 2 beneath. Incorporated into the upper arm of this relief pipe there is a valve casting 22 which is connected into the bottom of the arm 10 by means of a tube 23.

In the casting 22 there are the upper and lower valve seats 24 and 25 through which the liquid flowing through the relief line 21 must pass. These seats are controlled by the upper and lower disc valves 26 and 27 which are arranged above the corresponding seats 24, 25 and which are fixed on a valve stem 28 within the tube 23 and whose upper end is connected to the float stem 14 between the float and the adjusting rod 17.

The valve stem 28 extends beneath the lower seat 25 and fixed on said extended end there is a perforated disc 29 forming a stop to limit the upward movement of the valves.

The balanced valve mechanism above described has been provided to control the flow of reflux from the stripping tray 6 through the pipe 21 into the tray 2 beneath.

Should it be desired to change the level at which the liquid is to be maintained in the stripping tray 6 this may be readily done by adjusting the rod 17 and the corresponding end of the stem 14 upward or downward.

In order to assure the true vertical movement of the adjusting rod 17 its lower end is reduced and works in an upstanding tubular guide 30 in the bottom of the arm 10 in the manner disclosed in said co-pending application above referred to.

The upper and lower ends of the float chambers 8 and 9 are connected into the fractionating tower 1, between the partition 6 and the bubble tray

2 above by means of the respective upper and lower tubular nipples 31, 32 and 33, 34 which are equipped with the shut-off valves 35, 36 and 37, 38, respectively.

The upper and lower arms of the relief pipe 21 are equipped with the shut-off valves 39 and 40 and these arms are connected by a by-pass pipe 41 which is equipped with the shut-off valve 42 and which is located inwardly of the valves 39 and 40.

The respective float chambers are provided with drain pipes 43 and 44 which are provided with the shut-off valves 45 and 46 for drainage purposes.

Normally the valve 42 will be closed and the valves 39 and 40 open but if for any reason it should be desirable to by-pass the balanced valve mechanism 22 the valves 39 and 40 may be closed and the valve 42 open.

There is a discharge line 47 whose inner end extends inwardly through the wall of the fractionating tower and is sealed therewith and is upwardly turned and extends through the partition 6. This discharge line 47 is equipped with a balanced valve mechanism 48 similar to the mechanism of the valve 22 and which is operated by the valve stem 49 located in the tube 50 and whose upper end is connected to the float stem 15.

The outer end of this float stem 15 is connected to an adjusting rod 51 similar to the rod 17 but whose upper end is connected to a flexible diaphragm 52 which spans the diaphragm casing 53.

An air line 54 is connected, at one end, into the top of the casing 53 and, at its other end, it is connected into a conventional temperature control equipment 60. There is a thermo-couple 55 which is located in the fractionating tower chamber just beneath the partition 6, and this thermo-couple is connected with the temperature control instrument 60 by the positive and negative conductors 61, 62. The temperature control instrument has an air output from zero to fifteen pounds per square inch.

On opposite sides of the balanced valve mechanism 48 there are the shut-off valves 56, 57, incorporated into the line 47 and connected into the line 47 on opposite sides of the valves 56, 57 there is a by-pass pipe 58 incorporated into which there is a cut-off valve 59.

Normally the valves 56, 57 will be open and the valve 59 closed; however, if for any reason it should be desired to by-pass the balanced valve mechanism 48 this may be done by closing the valves 56, 57 and opening the valve 59.

The temperature controller is of such design that with a decrease in the temperature signal there will be an automatic decrease in the air output through the tube 54 against the upper side of the diaphragm 52. Should there be a change in the distillation process that would cause a temperature decrease in the tower chamber beneath the partition 6, and should said decrease be below a point selected by the operator, the thermo-couple 55 would be correspondingly affected and would in turn affect the temperature control instrument, through the conductors 61, 62 and should the decrease in temperature be out of harmony with the setting on the temperature control instrument the air output through the air line 54 would be decreased. This decrease in the air pressure will allow the compression spring 63 below the diaphragm 52 to move the diaphragm upwardly and the rod 51, being connected to said diaphragm, will be moved

upwardly also. The float 13, however, will remain in its same position. The float stem 15 will, therefore, be moved upwardly, thus lifting the valve stem 49 and opening the valve 48 to permit an increase in the flow of liquid from the stripping tray 6 through the distribution line 47 to a storage tank (not shown). The movement of liquid through the lines 47 and 34 will continue until the levels in the stripping tray 6 and within the housing 9 reach such a point as to cause the float 13 to be lowered; and, operating through the stems 15 and 49, will close the valve 48 and reduce the flow of liquid. The valve 48 will close before the stripping tray 6 has become empty.

At the same time, the level of the liquid in the chamber 8 will assume the same level as that in the chamber 9 and stripping tray 6, which level will be beneath that of the level before the temperature decrease. Therefore, upon downward movement of the float 12, the valve 22 will also be closed, thus reducing the cooling reflux flow through the line 21 to the tray 2 below the stripping tray 6, thus causing the temperature in the chamber beneath the stripping tray 6 to rise to its original, the selected, temperature.

Should the temperature in the chamber beneath the stripping tray 6 rise, the automatic control instrument 60, under the influence of the thermo-couple 55, will increase the air pressure above the diaphragm 52, forcing it downwardly and closing the valve 48, thus resulting in a rise of the liquid level in the float chambers 8 and 9, and in the stripping tray 6. This action will cause the float 12 to rise and correspondingly open the valve 22, allowing an increase in flow of liquid through the line 21 into the tray 2 beneath and thus bringing the temperature within the chamber beneath the stripping tray back down to its selected point; thereupon the float 13 will take control and re-open the valve 48 so that the level of the liquid in the tray 6 will not become abnormal.

What I claim is:

45. Automatic controlling means for a fractionating tower having an upper stripping tray and a lower bubble tray therein, a reflux line leading from the stripping tray and discharging into the bubble tray beneath, a discharge line leading out of the stripping tray, float chambers on a common level, upper and lower tubular nipples connecting the upper and lower ends of the respective float chambers into the stripping tray, shut off valves controlling said nipples, a reflux valve controlling the flow of liquid through the reflux line, a discharge valve controlling the flow of liquid through the discharge line, manually adjustable means controlled by the level of the liquid in one of said chambers and controlling the reflux 50 valve, means for controlling the discharge valve, said means being connected to the discharge valve and including a float in the other chamber and also including a diaphragm adapted to be placed under fluid pressure to move the discharge valve 55 toward closed position, a temperature controlling device responsive to the temperature in the tower and effective to apply said pressure upon an increase of the temperature in the tower and to relieve said pressure upon a decrease of temperature in the tower and mechanical means effective to move the discharge valve toward open position upon relief of said pressure.
